Primary Examiner — Shannon W Morgan*Assistant Examiner* — Keith Frank(74) *Attorney, Agent, or Firm* — Peter Giancana(57) **CLAIM**

The ornamental design for a perfume bottle, substantially as shown and described.

DESCRIPTION

FIG. 1 is a front perspective view of our new design for a perfume bottle;

FIG. 2 is a front elevation view of the perfume bottle shown in FIG. 1;

FIG. 3 is a rear elevation view of the perfume bottle shown in FIG. 1;

FIG. 4 is a right side elevation view of the perfume bottle shown in FIG. 1;

FIG. 5 is a left side elevation view of the perfume bottle shown in FIG. 1; and,

FIG. 6 is a top plan view of the perfume bottle shown in FIG. 1.

The long dash broken line represents the bounds of the claim and form no part of the claimed design. The small dashed broken lines in the drawings showing the perfume bottle illustrate the portions of the perfume bottle that form no part of the claim.
